UNITED STATES PATENT OFFICE.

NATHAN KASDAN, OF NEW YORK, AND DANIEL POLLACK, OF BROOKLYN, NEW YORK,
ASSIGNORS TO MAJESTIC MACHINE & TOOL CO., INC., OF NEW YORK, N. Y., A COR-
PORATION OF NEW YORK.

VANITY BOX.

Application filed February 26, 1924. Serial No. 695,178.

To all whom it may concern:

Be it known that we, NATHAN KASDAN, a citizen of Russia, and a resident of Bronx, in the county of Bronx, city and State of New York, and DANIEL POLLACK, a citizen of the United States, and a resident of Brooklyn, Kings County, New York, have invented certain new and useful Improvements in Vanity Boxes, of which the following is a specification.

The invention relates to improvements in vanity boxes or cases of the class adapted to contain a mirror and hold a compact of toilet powder and a compact of rouge, with the necessary pads or puffs, and said invention consists in the novel features and combinations of parts hereinafter described, and particularly pointed out in the claims.

In accordance with our invention the powder compact is formed in a cup which snugly fits within the body portion of the box, well below the upper edge thereof, and we provide an insert for the cover of the box carrying a slidable mirror frame holding a mirror, said insert being of ring formation and adapted to receive a cup within which the rouge compact is formed, and said mirror frame being adapted to lie upon the ring member and over the rouge compact and to be slid outwardly therefrom so as to expose the rouge and position the mirror for use.

The object of the invention is to provide a vanity case of the class referred to which shall be durable and convenient of use and the parts of which are compact and adapted to be held within a box or case of moderate dimensions. One feature of the invention is to provide a vanity box or case in which the body and cover portions are adapted to receive metallic cups in which the powder compact and the rouge compact are formed, said cups being readily removable so as to be replaced, when necessary, by cups containing fresh compacts.

A further feature of the invention resides in the provision of adequate means for slidably mounting the mirror frame on the frame which receives the rouge compact and to so proportion these frames that when the box is open the mirror frame may be slid outwardly to expose the rouge compact and that when the box is closed the mirror frame will lie within the upper portion of the body of the box above the puff which rests

upon the face powder compact. Our invention also provides means for latching the cup containing the rouge compact detachably in position.

The invention will be fully understood from the description hereinafter presented, reference being had to the accompanying drawing, in which:

Fig. 1 is a central vertical longitudinal section through a vanity box embodying our invention, the box being shown in open position exposing the face-powder compact, located in the body of the box, the rouge compact, located in the cover portion of the box, and the mirror which is shown in its outwardly extended position;

Fig. 2 is a front elevation of the same, taken from the right hand side of Fig. 1;

Fig. 3 is a central vertical longitudinal section through the box, shown in closed position;

Fig. 4 is an enlarged top view of the insert or attachment provided for the cover portion of the box, one member of said insert being of ring formation and having an open center to receive the cup for the rouge compact and the other member of the insert being a slidable frame for holding a mirror and mounted on said ring member, the glass mirror being omitted;

Fig. 5 is a plan view of the insert shown in Fig. 4 when the members thereof are slid together, the latch for retaining the rouge-cup being shown in its inoperative or reversed position in Fig. 4 and in its operative or securing position in Fig. 5;

Fig. 6 is a vertical section through the slidable mirror-frame and its mirror, taken on the dotted line 6-6 of Fig. 1;

Fig. 7 is a vertical transverse section, on an enlarged scale, showing the means for connecting the mirror-frame with the ring member held within the cover of the box, the section being taken on the dotted line 7-7 of Fig. 4;

Fig. 8 is a top view of a modified construction of insert for the cover of the box, the mirror-frame member, without the mirror, being shown in its outwardly extended position;

Fig. 9 is a central vertical longitudinal section through the same taken on the dotted line 9-9 of Fig. 8, the glass mirror being shown in its frame in Fig. 9;

Fig. 10 is a vertical transverse section

100

105

110

through the slidable frame carrying the mirror, taken on the dotted line 10—10 of Fig. 9, and

Fig. 11 is a vertical transverse section, on an enlarged scale, through the adjoining portions of the slidable mirror-frame and the rouge holding member, taken on the dotted line 11—11 of Fig. 8.

In the drawings, referring to Figs. 1 to 7 inclusive, 15 designates the body of the box and 16 the cover therefor, said body being cylindrical and of appropriate depth and connected by a hinge 17 with said cover 16, which is cylindrical and formed with a domed or convex top 18. A feature of the construction of the body 15 and cover 16 is that the rim of the cover is slightly less in diameter than the upper portion of the body 15 and, in the closed position of the cover, enters said body. The cover 16 is formed along its annular upper edge with an offset shoulder 19 which, in the closed position of the cover, seats upon and covers over the upper edge of the body 15, as shown in Fig. 3. At its front edge the rim of the cover 16 is formed with a slight projection 20 which snaps into a recess 21 of the body 15 when the cover is closed, for latching the cover in closed position. The body 15 detachably receives a metallic cup 22 within which the face-powder compact 23 is directly formed and which snugly fills the lower portion of the body 15, as shown in Fig. 1. Upon the compact 23 is loosely placed a puff 30 or pad 24.

The cover 16 receives an insert 25 which is of sheet-metal and ring formation and has a flat face section 14 and an outer edge flange 26 (Fig. 1) which closely fits within the rim of the cover 16. The insert 25 has a commodious open center 27, and around its inner edges said insert 25 is formed with an annular edge flange 28 and an inwardly extended angular flange 29 (Fig. 1) which is integral with the inner edge of the flange 28 and provides suitable means for snugly receiving and supporting a metallic cup 30 within which is formed the rouge-compact 31, said cup 30 along its outer edge being flanged laterally to seat upon the transverse surface of the angle flange 29, while the vertical portion of the flange 29 snugly encompasses the sides of said cup 30. Upon the rouge-compact 31 will be placed a puff or pad 32, as usual.

To the rear portion of the insert 25 is pivotally secured a rotary latch plate 33, and preferably this plate will be secured to the insert by an eyelet 34 (Fig. 1) struck up from the material of the plate 33 and inserted through an opening in the insert 25 and flanged under the said insert so as to permanently secure the plate 33 to the insert. The face 14 of the insert 25 is preferably recessed, as at 35, to receive the plate 33. The

plate 33 is semi-circular in outline, and when in its operative position shown in Fig. 1, extends at its then inner edge over the adjacent edges of the box 30 and puff 32, and when in that position the plate 33 serves to latch the cup 30 in position and to aid in retaining the puff 32 in position on the compact 31. When it is desired to remove the cup 30 for the purpose of supplying a new cup containing a compact, the plate 33 will be swiveled on the eyelet 34 from its operative position shown in Fig. 1 to its inoperative position shown in Fig. 4. When the plate 33 is turned to the position shown in Fig. 4, its edge which had overlapped the edge of the cup 30, becomes turned outwardly and then extends over the adjacent portion of the body 15 of the box, and said plate 33 when in this position allows the cup 30 to be withdrawn from and a new cup inserted into the opening 27 of the insert 25. The latch plate 33 is turned to its releasing position shown in Fig. 4 when the vanity box is open, and the box cannot be closed while the plate 33 is in its unlatched position, and hence the location of the plate 33 compels the turning of the plate to its closed position after a new box 30 has been applied to the insert 25, since otherwise the box itself cannot be closed.

We apply to the insert 25 a sheet metal frame 36 which is circular and of about the same diameter as the insert 25 and is adapted to receive a glass mirror 37. The frame 36 is in the form of a circular plate having an edge flange 38 which encompasses the bezel 39 for the mirror. The bottom of the frame 36 has raised portions 40 at opposite sides of its center against which the mirror seats so that the mirror has a firm even bearing within the frame 36 and is held thereon by the bezel 39 and from the fact that the outer edge of the flange 38 is spun over against the bezel, as shown in Figs. 1 and 6. The frame 36 is slidably mounted upon the insert or ring-member 25, being shown in its outer position in Figs. 1 and 4 and in its inner position in Figs. 3 and 5. There are several ways of mounting the frame 36 slidably upon the insert 25 and one of these is shown in Figs. 4 and 7. In the construction shown in Figs. 1 to 7 inclusive the bottom of the frame 36 contains a wide opening or slot 41 extending lengthwise of the frame and from edge portion to edge portion thereof, and at the sides of the slot 41 the frame is formed with strengthening and guiding ribs 42, and the means connecting the frame 36 with the insert 25 consists of a thin plate 45 stamped out from sheet metal and having two upper lateral oppositely extending arms 43 (Fig. 7) which bear against the ribs 42, and two longitudinal arms 44 which extend through holes formed in the front portion of the insert 25 and are bent

toward each other under the adjacent portion of said insert, as shown in Fig. 1. The plate 45 is rigidly affixed to the insert 25 by means of the arms 44, and the arms 43 of said plate, by projecting laterally over the ribs 42 of the frame 36, retain said frame flatwise upon the insert 25 and permit the frame to be slid outwardly from its inner position shown in Fig. 5 to its outer position shown in Fig. 4. When the frame 36 is slid outwardly it uncovers the rouge compact 31 for use and positions the mirror 37 for convenient use, the inclination of the mirror being controlled at the hinge 17. The body 15 of the box therefore holds the cup 22 containing the powder compact 23 and the pad 24, and the cover 15 holds the insert 25 and cup 30 for the rouge compact 31. The outer flat surface of the insert 25 is practically flush with the free edge of the rim of the cover 16, and said insert holds the frame 36 carrying the mirror 37. When the frame 36 is slid outwardly to carry the mirror to the position shown in Fig. 1, said frame extends rearwardly over and beyond the edge of the cover, and when the frame 36 is slid inwardly to close the mirror over the rouge compact, or to the position shown in Fig. 3, and the box is closed, the frame 36 extends downwardly into the upper portion of the body 15 and positions the mirror closely over the puff or pad 24 for the powder compact. It will be seen on reference to Fig. 3 that when the cover 16 is closed its rim enters the edge of the body 15, and that the frame 36 is below the cover proper and within said body 15.

The raised seats 40 for the mirror prevent the reverse face of the mirror from injury during the sliding movement of the mirror frame 36 along the arms 43 of the fastener-plate 45. The ribs 42 of the frame 36 and the arms 43 are below the horizontal plane of the mirror-seats 40, as shown in Fig. 7, and the ribs 42 stiffen those portions of the frame 36 adjacent to the slot 41 therein and present limited friction surfaces to rub against the arms 43 during the sliding movements of the mirror-frame 36.

The ring insert 25 closely fits within the cover 16 and may be secured therein by indentations in its flange 26 entering corresponding indentations in the rim of the cover 16, these locking indentations being common in boxes and corresponding with the indentations 20, 21 hereinbefore referred to and being indicated in Fig. 1 at the then upper end of the open cover 16.

The latch-plate 33 will preferably be formed with a heading along its edge, as shown, to stiffen and add a finish to the plate and to facilitate the operation of the plate by one's finger.

The ring insert member 25 and slidable mirror frame 36, with its mirror 37, con-

stitute an attachment to be applied to box-covers and may be made the subject of a separate article of manufacture to be sold to box makers.

In Figs. 8 to 11 inclusive, is shown a modified construction of insert or attachment and therein 46 denotes the circular insert member and 47 the mirror frame member. The member 46 is formed from one integral piece of sheet metal and has a flat upper face portion 48, an outer edge depending skirt or flange 49 to be forced into the box-cover, a central cup or receptacle 50 to receive a rouge compact 51, a lip 52 extending over one edge of the cup 50 to aid in retaining a puff on the compact 51 and spring fingers 53 in the sides of the cup 50 for securing the compact 51 in place.

The mirror frame 47 is in one integral piece of sheet metal and is circular in outline and of about the same diameter as the insert member 46. The member 47 has a vertical edge flange 54 to receive the bezel 55 for the mirror, two oppositely projected raised arcuate beadings or seats 56 for the mirror 57, two long longitudinal parallel slots 58 and two parallel ribs 59, one rib being adjacent to each of said slots.

The mirror-frame 47 is slidably connected with the insert member 46 by means of a fastener 60 which is a strip of metal whose body portion 61 bridges across the ribs 59 and whose end portions extend downwardly through the slots 58 and through holes 62 in the face of the insert member 46 and are then bent, laterally in opposite directions to form securing arms 63, as shown in Fig. 11. The fastener 60 is stationary with the insert member 46 and permits the mirror frame to lie over said member 46 or be slid outwardly therefrom to the position shown in Figs. 8 and 9. The attachment consisting of the members 46, 47 has the same operation as the attachment consisting of the members 25, 36 shown in Figs. 1 to 7 inclusive. In the construction shown in Fig. 9 the cup 50 is integral with the insert member 46 instead of being a separate cup, and the mirror frame 47 possesses in different structural form all the essential features of the mirror frame 36 of Figs. 1 to 7 inclusive.

What we claim as our invention and desire to secure by Letters Patent, is:

1. A vanity-box comprising a body portion to hold a powder compact and puff therefor, a cover hinged to said body portion at one edge thereof and adapted at its rim to close down into said body and an attachment applied to said cover comprising a circular insert member closely fitting within the rim of the cover and adapted to admit a rouge compact and its puff and a circular mirror frame holding a mirror and mounted on and connected with said insert member and adapted to cover the

same and also to be moved outwardly from over the same when the box is open, the means connecting the mirror frame with said insert member being rigid with the insert member and maintaining said frame and member parallel.

2. A vanity-box as claimed in claim 1, in which the insert member has a flat face portion on the plane of the free edge of the rim of the cover and in which the mirror frame may be slid over said edge when the box is open and also extend downwardly below said edge when the box is closed and enter the body of the box and lie above the powder compact therein.

3. A vanity-box as claimed in claim 1, in which the mirror frame is longitudinally slotted and in which the means connecting said frame with the insert member is a fastener having an upper portion engaging said frame, a portion extending through the slot thereof and a portion fastened to the insert member.

4. A vanity-box as claimed in claim 1, in which the mirror frame is longitudinally slotted to slide upon the means connecting the same to said insert member and in which said frame has raised seats for the mirror to clear the same from said connecting means.

5. A vanity-box as claimed in claim 1, in which the mirror frame is slotted to slide upon the means connecting the same with said insert member and in which said frame has raised seats for the mirror to clear the same from said connecting means and also raised ribs to ride against said connecting means when the mirror frame is slid outwardly and inwardly.

6. A vanity-box as claimed in claim 1, in which the insert member has an inwardly extending member to aid in retaining the rouge puff in position.

7. A vanity-box as claimed in claim 1, in which the mirror frame is longitudinally slotted to slide upon the means connecting the same with said insert member, and in which said means comprises a plate fitted to said slot and having laterally extending arms engaging the upper surface of said frame and depending arms extending through holes in the insert member and bent under said member.

8. A vanity-box as claimed in claim 1, in which the insert member has a flat circular face portion to receive the mirror frame and a member extending inwardly over one edge of the rouge compact from said face portion.

9. A vanity-box as claimed in claim 1, in which the insert member has a flat circular face portion to receive the mirror frame and a latch plate extending inwardly over one edge of the rouge compact from said face portion, said latch plate being pivotally

secured to the insert and adapted to be turned laterally from over the rouge compact. 79

10. A vanity-box as claimed in claim 1, in which said insert member has a flat circular face portion to receive the mirror frame and a circular open center portion to admit the rouge compact and its puff. 75

11. A vanity-box as claimed in claim 1, in which said insert member has a flat face portion to receive the mirror frame and a flanged opening to detachably receive and support a flanged cup holding the rouge compact. 80

12. A vanity-box as claimed in claim 1, in which said insert member has a flat face portion to receive the mirror frame, a flanged opening to detachably receive and support a flanged cup holding the rouge compact and a pivoted latch plate to extend over the edge of said cup, said latch plate being at the rear portion of the insert member adjacent to the hinge of the box and when turned to its inoperative position being adapted to extend over the adjacent portion of the body of the box. 85 90

13. A vanity-box as claimed in claim 1, in which the insert member has a flat face portion on the plane of the free edge of the rim of the cover and in which the mirror frame may be slid over said edge when the box is open and also extend downwardly below said edge when the box is closed and enter the body of the box and lie above the powder compact therein, and in which also the cover is formed around its upper edge with an annular shoulder to engage and seat against the upper edge of the body of the box when the cover is closed. 100

14. A vanity-box comprising a body portion having therein a removable cup holding a powder-compact and its puff, a cover hinged to said body portion and an attachment applied to said cover comprising a circular insert member having an edge skirt or flange closely fitting within the rim of said cover and a flanged opening to receive a cup holding a rouge compact and its puff and also means for detachably retaining said cup in position, and a circular mirror frame holding a mirror and mounted on and connected with said insert member and adapted to cover the same and also to be slid outwardly therefrom to expose the rouge when the box is open, the means connecting the mirror frame with said insert member being rigid with said member and said frame being slotted to slide upon said means. 110 115

Signed at New York city, in the county and State of New York, this 25th day of February, 1924. 120 125
